GEORGE PRUSSIAN, OF NEWARK, NEW JERSEY

INTERCHANGEABLE STONE SETTING FOR RING TOPS AND THE LIKE

Application filed June 4, 1927. Serial No. 196,427.

My invention relates to an interchangeable stone setting for ring tops and the like.

The object of the invention is the provision of a simple and inexpensive ring top construction for enabling any jeweler to set a stone in a ring securely without any cutting or beading over of the metal, and without the necessity of sending the job out to a skilled stone setter, and which will permit variation in the size of stones which can be used with each size of ring top.

The invention will be best understood from the illustrative embodiment thereof shown in the accompanying drawing, in which:

Fig. 1 is a top plan view of a ring embodying my invention.

Fig. 2 is an exploded view of the jewel in its holder, the ring top, and the nut for the holder.

Fig. 3 is a vertical sectional view on line 3—3, Fig. 1, showing the parts in relation after assembly has been started, but before its completion, and

Fig. 4 is a section on line 4—4, Fig. 1, showing the assembly completed.

The ring 10 may be of any construction, so long as it has an opening 12 therein for the reception of the ring top of my invention.

Preferably however the jewel holding portion of the ring is of hollow construction with openings therethrough, as shown, for permitting access of light to the base or undersurface of the jewel.

A ring top in accordance with my invention is designated generally by the reference character 14, and comprises a top plate or face plate 16 having a central opening 18 therein, with notches 20, 20 forming radial

extensions of said opening. Four of the notch extensions 20 are shown, but the number of these notches varies in practice with the shape of the top, as square, hexagonal, octagonal, etc. Depending from the plate 16

of the top 14 are side bars 22 of the yoke 24, formed with a hole 26 therein, in line with the opening 18 in the top plate 16. The top member 14 may be secured in the ring in any desired way, as for example, it may be soldered in place therein by the ring manufac-

turer. The yoke members may be of various forms, that shown being well adapted for permitting limited vision of the stone from the back.

The object which is to be set, as for example a stone 28, is received between the divergent arms 30, 30 of a spider member indicated generally by reference character 32, and which in the form shown is constructed from a piece of tubing which is cut lengthwise at one end and spread apart to form integral spider arms 30, which are bent over at their outer ends to form the hooks or beads 30', and has its uncut portion 34 threaded to receive the nut 36, and also has the tongues 38 cut in the end thereof, opposite the arms 30, for serving as locking members for holding the nut in place. The material at that part of the tube which is formed into tongues 38 is preferably trimmed off on the outside to a depth greater than the depth of the threads in the tube, so that the tongues 38 will not break off at the thread roots.

Jewelers carrying in stock rings embodying the top member 14 and also a quantity of the spider members 32 can permit their customers to select stones for setting therein according to the customers' fancy. In setting, the stone 28 selected is merely inserted between the spider arms 30 and under hooks or beads 30' and so held; the stem 34 is inserted through the two aligned openings 18 and 26; the nut 36 screwed on the screw-threaded stem 34, thus drawing the arms 30 inwardly in the notch extensions 20 provided for their reception and at the same time bringing them closer together, so that the stone is firmly and securely clamped and held by the spider in the ring top. After the nut 36 has been screwed up to the desired extent, it is locked in place by a locking means, as for example, by turning the tongues 38 outwardly into notches 40 provided for their reception in the surface of the nut 36.

It will be seen that with spider arms of different thicknesses different sizes of stones can be accommodated by variation of the extent to which the stones project above the top plate 14, a smaller stone being brought

down close to the top plate, and a larger stone projecting further above the top plate.

I may also provide a series of spiders having arms of varying thicknesses, so that the range of stone sizes which can be accommodated can be further extended, relatively thin spider arms permitting the use of relatively larger stones and thicker arms being adapted for relatively smaller stones, as will be obvious. The stone and spider combination must be sufficiently large to prevent the spider arms 30 from being drawn through the plate opening 18.

It will be apparent that the operations involved are all of a simple mechanical nature, and that the complete setting can be made and the appearance of an expensive hand-beaded setting secured by simply slipping a stone into a spider, inserting the spider 20 with the stone therein into the ring top, and applying a nut to the threaded portion of the spider, and all these operations are such as can be readily carried out by a jeweler, or by anyone accustomed to the use of jewelers' tweezers, and that by the construction shown, not only is the stone positively and firmly clamped in place and a great saving secured in time and in convenience of manipulation, but that both stones and rings can be readily 30 interchanged to suit the fancy and changing tastes of individuals. Furthermore by permitting access of light to the inner or under surface of the jewel, its brilliancy is greatly enhanced.

35 It will be plain that my invention can be applied to other pieces of jewelry, as bracelets, etc., and that the foregoing description of its application to a ring is not to limit me to such embodiment. Changes and modifications which may be made within the scope of my claims are included in my invention.

I claim:

1. An interchangeable stone setting for rings, comprising an apertured face plate, 40 with notches forming extensions of the aperture therein, a yoke behind said face plate, and side bar members connecting the yoke to the face plate, an aperture formed in said yoke in line with the first-named aperture, 45 but smaller, a jewel holder comprising a tubular member having integral diverging hooked arms at one end to be received in said notches and clamp a jewel in the face plate, the shank of said tubular member being threaded and 50 having lock tongues on the end thereof opposite said jewel holding arms, a nut adapted to be screwed on said threaded shank behind the yoke and thereby draw in the spider, 55 contract its arms and clamp the jewel, said nut having grooves on the face thereof remote from the yoke, and the tongues on the holder shank being bent outwardly to enter 60 said grooves and lock the nut against rotation.

2. A ring setting comprising an apertured face plate provided with notches forming extensions of said aperture, a jewel holder having divergent yieldable arms terminating in jewel engaging end portions and positioned within said face plate with said arms seated in said notches, the jewel holder being thereby held against rotation within the face plate, a threaded shank on said jewel holder, and threaded means coacting with said shank to draw the jewel holder into the face plate and force said arms inwardly to increase the grip of the jewel engaging end portions upon the jewel within the holder. 70

3. A ring setting comprising an apertured face plate provided with notches forming extensions of said aperture, a jewel holder having divergent arms terminating in hooks and positioned within said face plate with said arms seated in said notches, a threaded shank on said jewel holder, threaded means coacting with said shank whereby upon tightening up thereof and consequent progressive movement of said jewel holder into said face plate, said arms are contracted and the end portions increase their grip upon the jewel within the holder, and locking tongues on said shank beyond the threaded portion, adapted to lock the threaded means against rotation after the jewel has been securely 90 clamped within the holder. 95

4. A setting for rings comprising a face plate consisting of an upper and a lower part spaced apart and provided with aligned openings, the upper part being provided with notches forming extensions of the central opening; a jewel-holding spider having a threaded shank at one end and diverging arms at the other end, said arms terminating in inwardly directed hook or bead portions; the threaded shank of said spider being received in the lower part of the face plate and the spider arms being received in the face plate notches and thereby holding the spider against rotation; and threaded means coacting with the threaded spider shank for exerting a drawing action on the spider. 100

5. In an article of jewelry, a stationary member for receiving a setting having a hole in it and having notches constituting extensions of said hole; the lower portion of said member being formed into a yoke; a spider member having a stem, and arms terminating in inwardly directed hook or bead portions; a jewel within the spider member having a periphery adapted to substantially fit the hole in the setting member when the spider arms are received in the aforesaid notches and when the spider is drawn nearly but not entirely through the hole in the setting member, the spider member being held against rotation when its arms are seated in said notches; and means on the stem of the spider coacting with the yoke of the setting member behind the jewel for detachably holding the 110 115 120 125 130

- spider and stone in place in the setting member, whereby a replaceable setting is provided having substantially the appearance of a box-headed, hand-headed jewel setting.
- 5 6. A jewel setting comprising a body portion having an opening, a jewel supporting member within said opening and rigidly secured to said body portion, said member comprising a face plate forming a part of the exterior surface of the setting and having a central aperture with notches, a jewel holder separate from said face plate and having a body and divergent, integral, flexible jewel-holding arms within said notches, and means 10 cooperating with the jewel supporting member and jewel holder for moving the latter within the former in an axial direction to cause the jewel-holding arms to press inwardly against the jewel.
- 15 7. A jewel setting comprising a body portion having an opening, a jewel supporting member within said opening and rigidly secured to said body portion, said member comprising a face plate forming a part of the exterior surface of the setting and having a central aperture with notches, a jewel holder separate from said face plate and having a body and divergent, integral, flexible jewel-holding arms within said notches, and screw-threaded means cooperating with the jewel supporting member and jewel holder for moving the latter within the former in an axial direction to cause the jewel-holding arms to press inwardly against the jewel.
- 20 8. A jewel setting comprising a supporting member having an apertured face plate adapted to receive the jewel and form a border about the same, said face plate having notches extending outwardly from the aperture therein, a separate member adapted to be received within said first named member and having yieldable jewel engaging arms within said notches, whereby to permit of the use of the aperture to a maximum extent for receiving the jewel, and whereby to prevent rotation of the inner member, and means at the rear of said face plate cooperating with said members for drawing said inner member axially relative to the outer member and causing the arms to press inwardly against the jewel.
- 25 9. In a jewel setting, a support comprising apertured parallel portions joined by arms providing apertures therebetween, a jewel holder including spaced yieldable arms received within the aperture of one of said portions and having a camming engagement therewith, said yieldable arms serving to retain the jewel within the aperture and providing apertures communicating with the apertures between said first named arms, the opposite end of the jewel holder extending through the other apertured portion, and means coacting with the outer side thereof and with said jewel holder for uniting the parts together, and forcing the arms against the jewel.

10. A support for a jewel holder consisting of an apertured face plate portion to form a border for the jewel and an apertured abutment portion connected together in spaced relation to form an open structure, said apertures being disposed coaxially for receiving a pronged jewel holder, and the face plate portion having inner cam surfaces adapted to coact with the prongs of the jewel holder as the same is moved axially by means coacting with the outer side of said abutment portion.
- 70 11. In a jewel setting, a support consisting of an apertured face portion for receiving a jewel to form a border therearound and having interior camming surfaces, an apertured abutment portion, and arms connecting the portions to form an open structure, the apertures in said face and abutment portions being arranged coaxially, a jewel holder having yieldable arms adapted to be received within said face portion and a threaded portion adapted to be received within said abutment portion, and a nut on said threaded portion for exerting a thrust on said abutment portion to cause said flexible arms to be moved inwardly by the action of the camming surfaces.
- 75 12. A jewel setting comprising a portion having an opening therein and provided with notches forming extensions of said opening, a spider member having yieldable arms terminating in jewel engaging end portions, said arms contiguous to said jewel engaging end portions being adapted to be received in said notches to hold said spider member against rotation, said jewel engaging end portions projecting above said portion, and threaded means upon said spider member for drawing it into said portion and clamping the jewel in place by inward movement of said arms.
- 80 13. A jewel setting comprising a member including a face portion and a portion at the rear thereof, said portions having an axial opening therethrough, said rear portion forming an abutment at the end thereof, and the face portion having notches therein forming extensions of the opening thereof, a separate member received into said opening and including a shank portion and yieldable arms having jewel engaging end portions, said arms contiguous to said jewel engaging end portions being adapted to be received in said notches to hold the second named member against rotation, and means coacting with said shank portion and said abutment for drawing said second named member into said face portion to force said arms inwardly to grip the jewel.

100 In testimony whereof, I have signed my name hereto.

GEORGE PRUSSIAN.
